United States Patent Office

Des. 192,322
Patented Mar. 6, 1962

192,322

CIRCUIT BREAKER

David H. Dabney, Peekskill, N.Y., assignor to Federal Pacific Electric Company, a corporation of Delaware

Continuation of applications Ser. No. 53,321, Nov. 10, 1958; Ser. No. 53,322, Nov. 10, 1958; and Ser. No. 53,323, Nov. 10, 1958. This application May 17, 1960, Ser. No. 62,217

Term of patent 14 years

(Cl. D26—13)

FIG. 1

FIG. 2

FIG. 3

FIG. 4

FIG.5

FIG.6

FIG.7

FIG.8

FIG. 9

FIG. 10

FIG. 11

FIG. 12

FIG. 1 is a side elevational view of a circuit breaker, showing my new design as applied to a single-pole circuit breaker, the opposite side being substantially a mirror image thereof;

FIG. 2 is a top plan view of the circuit breaker shown in FIG. 1;

FIG. 3 is a fragmentary cross-sectional view, taken on line 3—3 in FIG. 1;

FIG. 4 is a perspective view of the circuit breaker shown in FIGS. 1, 2 and 3;

FIG. 5 is a side elevational view of a circuit breaker, showing my new design as applied to a two-pole circuit breaker, the opposite side being substantially a mirror image thereof;

FIG. 6 is a top plan view of the circuit breaker shown in FIG. 5;

FIG. 7 is a fragmentary cross-sectional view, taken on line 7—7 in FIG. 5;

FIG. 8 is a perspective view of the circuit breaker shown in FIGS. 5, 6 and 7;

FIG. 9 is a side elevational view of a circuit breaker, showing my new design as applied to a 3-pole circuit breaker, the opposite side being substantially a mirror image thereof;

FIG. 10 is a top plan view of the circuit breaker shown in FIG. 9;

FIG. 11 is a fragmentary cross-sectional view, taken on line 11—11 in FIG. 9; and

FIG. 12 is a perspective view of the circuit breaker shown in FIGS. 9, 10 and 11.

The dominant features of my new design are shown in solid lines in the drawings, and the common features

of the three illustrated embodiments of my new design consist primarily of a continuous concave elevated surface extending across the face of the circuit breaker with reversely curved structure projecting from the concave surface and a tapered handle extending from such reversely curved structure.

This application is a continuation of applications Serial Nos. 53,322, 53,321 and 53,323 filed November 10, 1958, now abandoned.

I claim:

The ornamental design for a circuit breaker substantially, as shown and described.
